UNITED STATES PATENT OFFICE.

SYLVESTER J. TUCKER, OF RICHMOND, VIRGINIA.

REFRIGERATING-CAR.

SPECIFICATION forming part of Letters Patent No. 301,776, dated July 8, 1884.

Application filed March 26, 1884. (No model.)

To all whom it may concern:

Be it known that I, SYLVESTER J. TUCKER, a citizen of the United States, residing at Richmond, in the county of Henrico and State of Virginia, have invented certain new and useful Improvements in Refrigerating-Cars, of which the following is a specification, reference being had therein to the accompanying drawings.

10 This invention relates to certain new and useful improvements in refrigerating-cars; and it consists, essentially, first, in constructing the flooring with a filling of non-conducting material, the doors and side walls with a dead-air space, and a filling of like material, the said walls having strips to retard the circulation of the air extending alternately therefrom into the space between them, and a dead-air space between the ceiling and the sheathing, 15 and a layer of non-conducting material between the latter and the roof; and, second, in providing an ice-crate composed of a series of depending hooks detachably connected at their lower ends with a series of bars, a plate 20 for collecting the condensation of moisture, and a trough connected therewith, so as to carry off such condensation.

In the accompanying drawings, forming a part of this specification, and on which like 30 letters of reference indicate the same, or corresponding features, Figure 1 represents a longitudinal sectional view of my improved refrigerating-car, showing the ice-box at the ends. Fig. 2 represents a perspective cross-sectional view of the car. Fig. 3 is a horizontal section of one of the side walls.

The letter A designates the frame of a car, and the letter B indicates a dead-air space, the sides of whose respective walls are provided with projecting strips or portions C, which alternately extend from the opposite sides thereof, their object being to retard the free circulation of the air contained between the walls.

45 The letter D refers to the space existing between the inner wall of the dead-air space and the inner wall of the car, the same being filled with mineral-wool or any non-conducting material, the object of which is to confine the 50 inclosed air and prevent the ingress of the warmer exterior air. I have found that non-conducting material is not sufficient of itself

to render the interior of a car impervious to the influences of the exterior air, and that the best results are attained when an air-chamber 55 or dead-air space is combined therewith, and I have therefore adopted this manner of construction in order to reduce the waste of ice to the minimum.

The letter E refers to the flooring of the car, 60 upon which is placed a layer, F, of any non-conducting material, the flooring proper, G, of the car being placed thereon.

The letter H designates the joists of the upper portion or top of the interior of the car, 65 having a ceiling, H', constructed of boards, a dead-air space, I, existing between this ceiling and the sheathing K, which is laid upon the rafters K'. Above this ceiling the roof L is constructed, preferably of wood, and in any 70 approved manner, and is supported at intervals by studs or strips L', thereby forming a space between it and the sheathing. This space is filled with an intervening layer, M, of non-conducting material.

The letter N indicates the hatchways, which open into the roof of the car, the same being provided with hatches or covers, and situated at the ends of the car directly above the ice-boxes. Beneath them are hatchways O', which 80 lead to the ice boxes or crates, and which are provided each with a hatch or cover. The space between the roof and ceiling between these respective upper and lower hatches is inclosed by the walls O".

The letter P designates a door in the side of the car, the same being constructed of two portions, Q and Q', each of which consists of an inner, an intermediate, and an outer wall. Between the inner wall and the intermediate 90 wall a filling of non-conducting material is placed. The space between the intermediate and outer walls constitutes a dead-air space, these walls being kept apart by the sleeves Q", and the several parts being bound together by the through-bolts Q', the contiguous ends of the doors being beveled, in order to form a better joint. These doors on the exterior of the car are covered by a sliding door, Q", mounted in suitable ways secured to 100 the outer side of the car, to more effectually exclude communication between the interior and the exterior of the car, its point of contact with the car inclosing the joints between

the door portions Q and Q' and the sides of the car.

The letter T represents a series of depending hooks, the upper ends of which are pivotally united with one of the joists H of the car, their lower ends being united together by a transverse rod, V. A series of bars, W, are pivotally connected with the ends of the car, and terminate at the other end in hooks, which fit over the transverse rod V. This structure forms the ice box or crate.

The letter X indicates what I term a "condensing-plate," the same being formed of sheet metal and curved at its lower end, so as to extend partially under the bottom of the crate, and attached at its upper end to the top of the car-frame.

Extending from the end of the car, and attached thereto, is a sheet-metal plate, Y, having a projecting stud on its underside, against which abuts the arm A', which is used to support the plate Y.

Attached to the opposite sides of the car, and running transversely of the same, is a trough, B', one end of which is slightly elevated above the other, so as to allow the drippings resulting from the condensation of moisture upon the plates X and Y to be conveyed to the pipe C', which communicates with the exterior. The pipe C' is bent near the bottom of the car, as shown at D', the object of which is to form a trap, so as to prevent the ingress of the exterior air.

It is to be observed that, by reason of the construction of the condensing-plates and the trough and pipes in connection therewith, whatever moisture might collect thereon will be immediately conveyed away and the air in the interior of the car thereby kept dry and pure.

It is further to be observed that an ice-box constructed of rods in the manner above described allows the greatest exposure of ice, thereby realizing the greatest amount of cold for a given amount of ice.

It will be seen that the construction of my improved ice-box is such as to allow of its ready removal in case it is desired to use the car as an ordinary freight-car. This latter I effect as follows: The condensing-plate X is, by means of the lug E', fastened to a link connected with the ceiling of the car, and the hooks T and bars W being disconnected, the latter, by force of gravity, fall against the end of the car, and the former are swung up toward the ceiling and engaged by a hook. The plate Y being slightly elevated, the arm A'

drops from its engagement with the stud, and the plate Y falls in like manner. It will thus be seen that all the parts are detachable and the space entirely cleared, leaving the car perfectly free from any obstruction whatever, and in a condition to be used as any ordinary freight-car.

Having thus fully described my invention, what I claim as new, and desire to secure by Letters Patent, is—

1. In a refrigerating-car, the side walls having dead-air spaces, from the respective walls of which alternately extend strips to retard the circulation of air and equalize the temperature.

2. In a refrigerating-car, the combination, with the pivoted hooks connected at their lower ends, of the series of pivoted bars detachably connected with said hooks, whereby an ice-crate is formed.

3. In a refrigerating-car, the combination, with the pivoted hooks and the series of pivoted bars connected therewith, of the condensing-plates, the transverse drip-trough, and the discharge-pipe.

4. In a refrigerating-car, the combination, with the hatchways in the roof and ceiling, provided with suitable hatches, of the pivoted hooks and the pivoted bars connected therewith, whereby an ice-crate is formed, and means to feed the same provided.

5. In a refrigerating-car, the combination, with the side walls having a dead-air space and a layer of non-conducting material, of the hinged doors having a dead-air space and a layer of non-conducting material, the dead-air spaces between the walls and doors having direct communication, and the outer sliding door.

6. In a refrigerating-car, the transverse joists, the ceiling laid thereon, the rafters, the sheathing laid thereon, the strips or studs, and the roof supported by said studs, a dead-air space being provided between the ceiling and the sheathing, and a layer of non-conducting material between the sheathing and the roof, the side walls having dead-air spaces, the alternating strips extending therefrom, a filling of non-conducting material, the doors having a communicating dead-air space, an adjacent filling, and the flooring having a like filling.

In testimony whereof I affix my signature in presence of two witnesses.

SYLVESTER J. TUCKER.
